United States Patent Office

Des. 220,950
Patented June 22, 1971

220,950

CHAIR

Leonardo D. Sideri, 1809 Gough St.,
San Francisco, Calif. 94109

Filed July 31, 1969, Ser. No. 18,484

Term of patent 14 years

Int. Cl. D6—01

U.S. Cl. D15—1

FIG_1

FIG_2

FIG_3

FIG_4

FIG_5

FIG_6

FIG. 1 is a view in perspective looking from the front of a chair embodying my design.

FIG. 2 is a view in perspective of the same looking from the rear.

FIG. 3 is a view in front elevation of the same.

FIG. 4 is a view in side elevation of the same, both sides having the same appearance.

FIG. 5 is a view in rear elevation of the same.

FIG. 6 is a top plan view of the same.

I claim:

The ornamental design for a chair, substantially as shown and described.
